UNITED STATES PATENT OFFICE.

CHARLES OSEAN, OF WOODCLIFF, NEW JERSEY, ASSIGNOR TO UNION CARBIDE & CARBON RESEARCH LABORATORIES, INC., A CORPORATION OF NEW YORK.

FLASH LIGHT.

Application filed March 4, 1922. Serial No. 541,137.

To all whom it may concern:

Be it known that I, CHARLES OSEAN, a citizen of the United States, residing at Woodcliff, in the county of Hudson and State of New Jersey, have invented certain new and useful Improvements in Flash Lights, of which the following is a specification.

This invention relates to portable electric lamps energized by a battery composed of 10 separate cells placed side by side and removably mounted in a casing.

It has heretofore been proposed to use unit cell batteries in electric lamps of the 15 flat flashlight type, and various means have been devised with this end in view. The present invention embodies improvements in structures of this type. It has for its 20 principal objects the provision of simple and effective cell holding and circuit completing means.

In general, the invention comprises a frame consisting of an upper plate rigidly secured to the flat wall of the flashlight casing, and a lower plate loosely mounted in the casing and attached by springs to the upper plate. The cells are inserted between 25 the plates and are securely held in operative position by the contractile force of the 30 springs. The frame is so constructed as to connect the cells in series. The elimination of connecting wires effected in this way, is a particular advantage of the invention. Further objects and advantages will be 35 apparent from the succeeding description.

The invention described herein is a modification of the invention broadly claimed in my application Serial No. 544,018, filed March 15, 1922.

40 In the accompanying drawings, which illustrate a preferred embodiment of the invention,

Fig. 1 is a front elevation of the lamp, the cover being in open position,

45 Fig. 2 is a vertical central section, on line II-II of Fig. 1, and

Figs. 3 and 4 are views taken respectively on lines III-III and IV-IV of Fig. 1, looking in the directions indicated by the 50 arrows.

Referring to the drawings, 1 indicates a flat metal casing comprising a cover 2 hinged at 3. The embodiment of the invention which has been selected for illustration is intended for use as a pocket flash-

light, and the casing is therefore rounded at its margin, so that it may fit conveniently into the pocket of the user. The dimensions and contour of the casing are adapted to the ordinary cylindrical flashlight cells. Any desired configuration of the casing may be chosen, however, with a view to the intended use of the lamp or the shape of the battery cells. Projections 4 are stamped in the side of casing 1 and engage a depressible locking catch 5, of known type, when the cover is closed.

A bulb holder 6 having a threaded stem 7 is mounted in one end of casing 1. The holder is partly received within a semicircular recess 8 in the casing wall and is secured to the wall by soldering, or in any other suitable manner. A corresponding recess 9 in the cover 2 fits over the projecting portion of the holder when the cover is in 75 closed position. The exterior rim of the holder is preferably substantially flush with the surface of the casing. A lamp bulb 10 is screwed into the stem 7 and the outer terminal of the lamp is in electrical contact 80 with the stem. The central lamp terminal 11 extends below the end of the stem and engages contact member 12, preferably of spring metal, which is secured by metal rivet 12' to the upper part of the cell supporting 85 structure.

This structure comprises, as its principal elements, a metal bracket 13, secured by soldering or other suitable means to the wall of casing 1, and upper and lower plates 90 14 and 15, of insulating material. Coil springs 16 and 17 are attached to the upper plate 14 and the lower ends of these springs are secured to the bottom plate 15. The normal length of the springs is such that 95 they must be somewhat expanded in order to insert the cells between plates 14 and 15. Spring 17 is in electrical contact with rivet 18 which passes through the bottom plate 15, by way of connector strip 19, and with 100 rivet 20 which passes through the top plate 14, by way of connector strip 21. This spring is not in circuit with the casing. Contact member 12 is also insulated from the casing. 105

A switch 22 is secured to the casing, and insulating plate 15 is cut away at 23 to permit the movement of the switch into circuit closing position.

Cells 24 and 25 are shown in outline in 110

Fig. 1. The electrical circuit in which these cells are series connected may be traced as follows: Through cell 24 to rivet 20, conductor strip 21 and spring 17, down through spring 17 to conductor strip 19, rivet 18, and cell 25, from cell 25 to rivet 12', contact strip 12 and the central lamp terminal, through the filament to the exterior terminal of the lamp and thence to the casing and 10 switch 22, finally through the switch 22 to the zinc base of cell 24.

The lamp is made ready for service merely by the insertion of the two cells, which have the usual paper wrapping or other lateral 15 insulation, the frame providing the necessary conductive parts for connecting the cells in series. As the dimensions of the closed case are such that no undue freedom of motion is allowed the cells, and as the 20 contact members are spring pressed against the electrodes, good electrical contact is permanently assured.

A metal casing has been described, but it will be understood that features of the 25 invention are applicable as well to non-conductive casings. The number and alinement of the cells, as shown, are preferable for pocket flashlights of the flat type. For other purposes or for casings of other kinds, 30 however, the battery may be composed of a different number of cells, the frame parts being suitably duplicated to accommodate them. Various other changes may be made in the form and arrangement of parts, within 35 in the scope of the appended claims.

I claim:

1. A portable battery operated electric lamp, comprising a casing, a cell supporting frame therein comprising a rigidly mounted 40 plate, a movable plate, and spring means connecting the plates and adapted to exert compressive force upon a plurality of battery cells disposed between said plates, the supporting frame providing a conductive path for connecting the cells in series.
2. A portable battery operated electric lamp, comprising a casing, plates carrying contact members adapted to engage the terminals of a plurality of cells, and spring 50 means connecting the plates.

3. A portable battery operated electric lamp, comprising a casing, plates carrying contact members, a plurality of cells similarly arranged in the casing and with their electrodes in engagement with said contact 55 members, and spring means for connecting the plates.

4. A portable battery operated electric lamp, comprising a casing, a member rigidly mounted on said casing, an insulating plate 60 secured to said member, spring means extending from said plate, and a second insulating plate secured to the said spring means and adapted to be drawn thereby into contact with a plurality of battery cells. 65

5. A portable battery operated electric lamp, comprising a metallic casing, a metallic bracket secured thereto, an insulating plate carried by said bracket, coil springs extending from said plate, a 70 second insulating plate secured to said springs, contact members carried by said plates and adapted to engage the terminals of a plurality of battery cells, one of said springs being insulated from said casing 75 and forming part of a conductive path between cell terminals of opposite polarity.

6. A portable battery operated electric lamp, comprising a flat metal casing, spring-connected plates in said casing and adapted 80 to receive a plurality of cells therebetween, said spring-connected plates affording a conductive path for connecting a plurality of cells in series.

7. A portable battery operated electric 85 lamp, comprising a flat metal casing, a lamp bulb mounted therein, an insulating plate mounted in the casing and adjacent the bulb, a contact member carried by the plate and adapted to engage the central terminal 90 of the lamp, a second insulating plate attached by spring means to the first-mentioned plate, contact members upon said plates and adapted to engage the terminals of a plurality of cells, and means for connecting cells in series and establishing an electrical circuit through the contact member and the filament of the lamp. 95

In testimony whereof, I affix my signature.
CHARLES OSEAN.
